INTEGRATED VOICE AND DATA TELE- COMMUNICATIONS DESK STAND

Henry Dreyfuss, South Pasadena, Calif., and Robert H. Hose, Mountainside, and Herbert C. Illium, Jr., Edison, N.J., assignors to Bell Telephone Laboratories, Incorporated, New York, N.Y., a corporation of New York

Filed Mar. 15, 1961, Ser. No. 64,305

Term of patent 14 years

(Cl. D26—14)

FIG. 1

FIG. 2

FIG. 3

FIG. 1 is a perspective view of the integrated voice and data telecommunications desk stand showing our new design;

FIG. 2 is a side elevation thereof, the opposite side having substantially the same appearance; and

FIG. 3 is a top view thereof.

The characteristic features of our new design are shown in solid lines in the drawing.

We claim:

The ornamental design for an integrated voice and data telecommunications desk stand, substantially as shown and described.
